UNITED STATES PATENT OFFICE.

GORDON WAXEL, OF NEW YORK, N. Y.

CIGAR-BOX.

1,236,634.

Specification of Letters Patent. Patented Aug. 14, 1917.

Application filed June 16, 1916. Serial No. 104,002.

To all whom it may concern:

Be it known that I, GORDON WAXEL, a citizen of the United States, residing at New York, in the county of New York and State of New York, have invented certain new and useful Improvements in Cigar-Boxes, of which the following is a specification, reference being had therein to the accompanying drawings.

10 My invention relates to improvements in cigar boxes, and the objects contemplated are the provision of a container of this class which will preserve cigars in a moist condition without the coöperation of special humidi-
15 fiers; and to provide a container which may be manufactured and sold at a price sufficiently low to permit its general use.

To the accomplishment of the recited objects and others subordinate thereto, the preferred embodiment of my invention resides in that construction and arrangement hereinafter described, shown in the accompanying drawings, and embraced within the scope of the appended claims.

25 In said drawings:

Figure 1 is a perspective view of the container.

Fig. 2 is a transverse sectional view taken along lines 2—2 of Fig. 1.

30 Fig. 3 is a detail perspective view of the end and side panels removed, and

Fig. 4 is a fragmentary sectional view taken along lines 4—4 of Fig. 1.

Broadly, my invention comprises a box 35 having a closure, the bottom of the box and the inside of the closure being formed with inserts which are impervious with respect to air and moisture. The bottom insert is retained by the end and side panels, while the 40 top insert is sustained by cleats extending transversely of the closure.

Referring more particularly to the drawings, the numeral 10 designates a box provided with a lid or closure 11. On the inside 45 of the bottom 12 of the box is superposed a plate 13 of impervious material, such as glass. This insert is maintained in proper relation to the body of the box by the individually removable end and side panels, 14 and 15, respectively, which are pervious as 50 to moisture, formed preferably of unseasoned cedar, and disposed contiguous rela-

tively to the inner walls of the box. The adjacent edges of the panels are beveled, as at 16, and the upper edges rounded off so that 55 they will fit to a nicety and present a finished appearance. A companion impervious plate 17 is arranged inside of the lid 11, and fastened thereto by means of transverse cleats 18. When the lid is closed, as exhibited in Fig. 4, the confronting edges of the panels and the cleats engage each other and in this respect serve to form a sealed joint.

The function of the impervious plates or linings is to occlude the major area of the 65 sensible pores of the box and lid, and thereby prevent the absorption by these pores of the moisture from the cigars, or the like, which it is desired to keep in a state of preservation. At the same time, by reason 70 of the comparatively thick walls of the box and lid, as well as the seal therebetween, the panels of cedar are maintained normally charged with a certain amount of moisture, and but little of the moisture is absorbed 75 from the cigars while sufficient aromatic qualities of the cedar are absorbed to properly blend the cigars. If upon the other hand, the cigars are dry when initially placed in the container, the absorption 80 strength of the tobacco will be in excess of the absorption strength of the cedar, and thereby take up moisture and aroma from the cedar. As will be readily appreciated, this phenomenon makes it possible to pre- 85 serve already moistened cigars in a moist condition and to moisten dry cigars without the employment of special humidor devices and the constant attention which such devices require.

90 It should be understood that in its broader aspects my invention comprehends the employment not only of the means described, but of equivalent means for performing the recited functions. While the arrangement shown is thought to be preferable, it is desired to reserve the right to effect such changes and modifications as may come fairly within the scope of the appended claims.

100 What is claimed is:

1. A receptacle for cigars and the like, comprising an outer box-like casing having a hinged lid, a vitreous lining in said lid

and box bottom, and a lining of cedar panels for the ends and sides arranged to project above the box sides into the lid.

2. A receptacle for cigars and the like, comprising an outer box-like casing having a hinged lid, a vitreous lining in said lid and box bottom, and a lining of individually removable cedar panels for the ends and

sides arranged to project above the box sides into the lid.

In testimony whereof, I hereunto affix my signature, in the presence of two witnesses.

GORDON WAXEL.
